US00D944198S

(12) **United States Design Patent** (10) **Patent No.:** **US D944,198 S**
Wu (45) **Date of Patent:** **** Feb. 22, 2022**

(54) **WIRELESS CHARGER**

(71) Applicant: **Guanyuan Shengye (Shenzhen) Intelligent Technology Co., Ltd., Shenzhen (CN)**

(72) Inventor: **Manfang Wu, Guangdong Province (CN)**

(**) Term: **15 Years**

(21) Appl. No.: **29/779,537**

(22) Filed: **Apr. 20, 2021**

(51) LOC (13) Cl. **13-02**

(52) U.S. Cl.

USPC **D13/108**

Primary Examiner — Rosemary K Tarcza

(57) **CLAIM**

The ornamental design for a wireless charger, as shown and described.

DESCRIPTION

FIG. 1 is a front and top perspective view of a wireless charger, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the wireless charger that form no part of the claimed design.

1 Claim, 8 Drawing Sheets
